UNITED STATES PATENT OFFICE.

GEORGE N. THOMAS, OF MANKATO, MINNESOTA.

RADIATOR-PROTECTOR.

1,345,283.

Specification of Letters Patent. Patented June 29, 1920.

Application filed April 15, 1918. Serial No. 228,694.

To all whom it may concern:

Be it known that I, GEORGE N. THOMAS, a citizen of the United States, residing at Mankato, in the county of Blue Earth and 5 State of Minnesota, have invented new and useful Improvements in Radiator-Protectors, of which the following is a specification.

This invention has reference to an attachment for radiators of automobiles.

An object of the invention is to produce an attachment for this purpose which is in the nature of a plate designed to be received on the outer face of the radiator and having 15 louvers and openings therein so arranged as to permit of a greater volume of air passing through the upper portion of the radiator, to cool the top of the radiator and to protect the bottom thereof, and consequently 20 reduce the liability of freezing of the radiator, while not interfering with the proper circulation of air therethrough.

In cold weather the radiators for motor cars are protected from freezing by means 25 of some non-freezing solution or by emptying the radiator. The general practice when driving is to bundle the hood and radiator with a blanket or cover. The first result of this practice is the boiling of the radiator 30 incident to the fact that the proper amount of air is not admitted to the cooling system. Hot water always seeks a higher level, and consequently when the engine becomes overheated the water in the radiator is drawn to 35 the top allowing the water in the bottom of the radiator to freeze. With my improvement a correct distribution of air is allowed to flow through the radiator, when the car is driven, the greater volume of air being 40 delivered to the upper heated portion of the radiator, the lesser volume to the lower portion thereof which is most liable to freeze, and as a consequence preventing such freezing, while at the same time permitting of 45 the admission of a necessary flow of air through the radiator during warm weather so that the device may remain permanently fixed on the radiator.

With the above and other objects in view, 50 the invention consists in the construction, combination and arrangement of parts, as herein described, illustrated and claimed.

In the accompanying drawings,

Figure 1 is a front elevation of the radiator 55 of a motor vehicle, showing the im-

proved protector in its applied relation thereto.

Fig. 2 is a vertical sectional view through the protector shown in its applied relation to a radiator.

The protector contemplated in this invention, may be manufactured out of sheet metal and given any desired finish. The protector comprises a body 1 of sheet metal which is formed with a plurality of vertical 60 rows of air deflecting lips 2. These lips are provided by forming horizontal slits 3 in the body 1 and then swaging or pressing a portion of the metal just above the slits 3 forwardly, so as to project in front of the plane 65 of the body 1, thereby forming air admission openings 4 each of which is covered and protected by one of the deflecting lips 2.

In addition to the air admission openings above described, holes 5 of circular or other 70 shape may be provided along the vertical center and along the top marginal portion of the body 1 as shown in Fig. 1. The body 1 is made in a size to fit any particular radiator in connection with which it is designed 75 to be used. The dimensions of the body 1 are such as to enable the marginal edges thereof to be fitted under the forward top, side and bottom flanges 6, 7 and 8 respectively, of the casing 9 of the radiator, and 80 between said flanges and the core 10 of the radiator. It is preferred, to apply a gasket 85 11 of asbestos paper or the like to the rear marginal portion of the protector so as to form a cushion and anti-rattling filling between the sheet metal protector and the core 90 of the radiator. This will protect the radiator core and prevent any possibility of rattling between the protector and the casing 95 of the radiator.

From the foregoing description taken in connection with the accompanying drawings, it will now be seen that the air cannot strike directly against the lower part of the core of the radiator but is deflected by the 100 baffle lips 2 and caused to pass upwardly at an inclination.

The lower part of the radiator is most liable to freeze because hot water therein always rises to the top thereof. Most radiators freeze when the car is being driven, not while the car is standing idle. An idle car is protected either by a non-freezing solution or the emptying of the radiator. Because of the holes 5 arranged at the top of 105

the protector plate and in the center thereof, but terminating a distance away from the lower edge of the said plate, also by the arrangement of the baffle lips or louvers, the 5 inflowing air will tend to cool the upper and heated portion of the radiator so that the sides and bottom of the said radiator will be thus protected and the liability of freezing is reduced to a minimum. In summer time 10 ample air is admitted through the protector to keep the radiator cool, and the protector plate when once positioned need not be removed. In addition to reducing the liability of the freezing of the radiator to a 15 minimum the plate 1 prevents contact with the radiator from the outer face thereof,

and in this respect offers an additional protection therefor.

I claim:—

The combination with a radiator for an 20 automobile, of a protector, comprising a plate arranged on the outer face of the radiator, said plate at the sides thereof having horizontally disposed slots, outwardly extending upwardly inclined lips over said 25 slots, and said plate having openings adjacent to the top and in its center above the lower edge thereof, all as and for the purpose set forth.

In testimony whereof I affix my signature. 30

GEORGE N. THOMAS.
